UNITED STATES PATENT OFFICE.

CLAUS PETER CHRISTENSEN, OF BULL FROG, NEVADA.

ORE SEPARATOR OR FILTER.

No. 824,905.

Specification of Letters Patent.

Patented July 3, 1906.

Application filed October 5, 1905. Serial No. 281,555.

To all whom it may concern:

Be it known that I, CLAUS PETER CHRISTENSEN, residing at Bull Frog, in the county of Nye and State of Nevada, have invented 5 certain new and useful Improvements in Ore Separators or Filters, of which the following is a specification.

My invention relates to certain new and useful improvements in ore separating or filtering machines particularly adapted for use in connection with quartz-mills and the like for separating the tailings consisting of water and sand composed of ground-up ore from the batteries.

15 In its generic nature my invention comprises an endless absorbent belt, upon which the material to be separated is discharged in aqueous suspension or solution, means for driving said belt and supporting the same, a 20 trough for receiving the water which passes through the belt, a trough for receiving the solids which are discharged from the belt, and means for discharging any solids which 25 lodge on the belt into the trough.

Primarily, my invention has for its object 30 to provide a device of this character of a very simple and effective construction which can be easily manufactured and which will readily and effectively serve its intended 35 purposes.

With other objects in view than have been heretofore specified the invention also comprises certain novel construction, combination, and arrangement of parts, all of which 40 will be first described in detail and then be specifically pointed out in the appended claims, reference being had to the accompanying drawings, in which—

Figure 1 is a perspective view of my invention. Fig. 2 is a side elevation thereof. Fig. 3 is a top plan view of my invention. Fig. 4 is a vertical longitudinal section thereof on the line 4 4 of Fig. 3. Fig. 5 is a detail horizontal section on the line 5 5 of Fig. 4. Fig. 6 is a cross-section on the line 6 6 of Fig. 4 looking in the direction of the arrow.

Referring now to the accompanying drawings, in which like numerals of reference indicate like parts in all of the figures, 1 designates the supporting - framework of the machine, which includes the horizontal top beams 1^a 1^a, near one end of which a shaft 2 is mounted in bearings 2^a 2^a, secured to the beams 1^a 1^a, as shown. The shaft 2 carries a belt-pulley 2^b, arranged between the beams 1^a 1^a and a sprocket-wheel 2^c on the

outside of the framework. At the other end adjusted bearings 3 are secured to the beams 1^a 1^a and are adjustable by the screws 3^a, as shown. In the bearings 3 a second shaft 4 of like construction to the shaft 2 is mounted, and the shaft 4 carries a belt-pulley 4^b, around which and around the pulley 2^b an endless separating-belt 5 is passed. The belt 5 consists of heavy burlap or other suitable porous material and is provided at each edge with endless ropes 5^a 5^a, which serve to form upturned edges for the belt to prevent the material from overflowing the same.

Above the main frame 1 and held between the belt 5 just below the upper portion thereof and upon the supplemental frame 10 a trough 6 is mounted, which extends from the one pulley 4^b to the other pulley 2^b and is provided with flange portions 6^a 6^a, as shown, the trough 6 serving to collect the water which filters through the belt 5 and discharges the same through the outlet-spout 6^b. Mounted above the trough 6 in bearings 7^a, secured to the supplemental frame 10, are a series of rollers 8, which receive the belt 5 and guide and hold the same and serve as belt-carrying rollers. Mounted in bearings 9 on the beams 1^a 1^a is a shaft 9^a, which carries a sprocket-wheel 9^b, around which and around the sprocket-wheel 2^c an endless chain 11 passes. The shaft 9^a also carries a gear-wheel 12, which meshes with a pinion 13 on a drive-shaft 14, mounted in bearings 14^a on the beams 1^a 1^a, which shaft 14 is driven by the pulleys 15 and 16, as shown, the pulleys 15 and 16 being tight and loose pulleys, as well understood from the drawings. Meshing with a pinion 13 on the side opposite to the gear 12 is a second gear 17, mounted on a shaft 18, that carries a sprocket 19, and said shaft is mounted in bearings 20 20 on the beams 1^a 1^a, as shown. Around the sprocket 19 and a coöperating sprocket 21 on a shaft 22, that is mounted in bearings 22^a on the beams 1^a, is an endless chain 23, by means of which the motion of the shaft 18 is imparted to the shaft 22.

23 23 designate cam members carried by the shaft 22 for tripping the horizontally-pivoted bars 24 24, which carry tamping or impacting feet 25 25, that engage or impact on the belt 5 in a manner presently understood.

27 27 designate coil-springs secured to a beam 27^a, forming a part of the supplemental frame 10, which springs normally force the

bars 24, with their feet 25, into engagement with the belt 5. A pair of leaf-springs 28 serve to engage the bars 24 to normally hold the feet 25 just out of engagement with the belt 5, as shown in Figs. 4 and 5. The bars 24 are pivoted at 24^a to a cross-beam 24^b, as shown.

28^e designates a roller mounted in bearing-sprockets 28^a beneath the beams 1^a 1^b, over which the belt 6 takes.

30 designates a trough mounted under the roller 4^b and extending backwardly therefrom, which trough 30 is adapted to receive the solid material from the belt 5 in a manner presently understood.

31 designates a supply-trough, from which the material is fed onto the belt 5, and the trough 31 is mounted above the belt 5, as clearly shown in the drawings.

So far as described the manner in which my invention operates will be best explained as follows: The material to be separated is run into the trough 31, from which it escapes onto the belt 5. Motion is imparted to the drive-shaft 14 in the direction of the arrow in Fig. 1 to turn the belt in the direction of the arrow in Fig. 1. The water from the trough 31 will filter through the belt 5 and flow into the trough 6, from whence it is drained through the spout 6^b and may be used over again, if desired. The solid matter as the belt 5 moves along drops therefrom into the trough 30, and should any material adhere to the belt and not drop in the trough 30 of its own gravity it will be dislodged from the belt 5 by the tamper-feet 25, which are actuated by the cams 23, as clearly understood by reference to the drawings, the cams 23 serving as trip-cams to trip the beams 24 to cause an impact to be given to the belt 5 to discharge the materials therefrom.

So far as described it will be seen that I have provided an apparatus of the class of a very simple and effective construction, which can be easily and cheaply manufactured, requiring the minimum amount of material, and which can be readily and effectively used to perform the function desired.

From the foregoing description, taken in connection with the accompanying drawings, it is thought the complete construction, operation, and many advantages of my invention will be readily understood by those skilled in the art to which it appertains, and I desire to say that many slight changes in the detailed construction, operation, and arrangement of parts can be made without departing from the invention or the appended claims.

Having thus described my invention, what I claim, and desire to secure by Letters Patent, is—

1. A machine of the class described, comprising a supporting-frame, a pair of pulleys mounted one at each end of the frame, an end-

lessseparating-belt taking around said pulleys, and an endless rope secured to each edge of said belt and movable therewith, means for depositing the material to be separated on said belt, means for receiving the solid material from said belt, means arranged between the pulleys beneath the belt for receiving the liquid material that passes through the belt, and means for driving said belt, substantially as shown and described.

2. An apparatus of the class described comprising a supporting-frame, a pair of belt-pulleys mounted in bearings, one at each end of said frame, an endless separating-belt of porous material passing around said pulleys, and an endless rope secured to each edge of said belt and movable therewith, a supplemental frame mounted on said supporting-frame between said pulleys and below said belt, belt-carrying rollers mounted on said supplemental frame, a water-receiving trough mounted on said supplemental frame, a solid-matter-receiving trough mounted below one of said first-mentioned belt-pulleys to receive the solid material, means for depositing the material to be separated on said belt, substantially as shown and described.

3. An apparatus of the class described comprising a supporting-frame, a pair of belt-pulleys mounted in bearings, one at each end of said frame, an endless separating-belt of porous material passing around said pulleys, and an endless rope secured to each edge of said belt and movable therewith, a supplemental frame mounted on said supporting-frame between said pulleys and below said belt, belt-carrying rollers mounted on said supplemental frame, a water-receiving trough mounted on said supplemental frame, a solid-matter-receiving trough mounted below one of said first-mentioned belt-pulleys to receive the solid material, means for depositing the material to be separated on said belt, means for tamping said belt to remove the solid material therefrom, and means for driving said belt and said tamping means, substantially as shown and described.

4. An apparatus of the class described comprising a main supporting-frame, a pair of belt-pulleys mounted in bearings at each end of said frame, means for adjusting one of said pulleys, an endless separating-belt passing around said pulleys, said belt having raised portions at each side thereof, a supplemental supporting-frame mounted on the main supporting-frame between the belt and the belt-pulleys, a water-receiving trough mounted on said supplemental frame below the belt, belt-supporting rollers over said water-trough, means for depositing the materials to be separated on said belt over said water-trough, a receptacle at one end of the main frame for receiving the solid matter from the belt, a guide-roller on the main

frame over which said belt takes, a tamping device supported by the main frame for tamping said belt to remove the solids therefrom, drive mechanism for said belt, means connecting said belt-drive mechanism with said tamping mechanism to operate the same, substantially as shown and described.

5 5. A device of the class described comprising a main supporting-frame, a belt-pulley mounted in bearings at each end of said supporting-frame, said belt-pulleys including shafts, an endless separating-belt taking over said pulleys, means for adjusting the tension of said belt, guide-rollers for the upper portion, a trough mounted over said belt from which the material is deposited on the belt, a water-trough below the upper portion of the belt to receive the percolated material, a receptacle at one end of the machine to receive 15 the solids from the belt, means for tamping said belt, cam devices for operating said tamping means, a drive mechanism connect-

ed with said cam devices and with one of said belt-pulleys to operate the same, substantially as shown and described.

25 6. A machine of the class described, comprising a supporting-frame, a pulley mounted at each end of the frame, an endless separating-belt taking around said pulleys, an endless rope secured to each edge of said belt 30 and movable therewith, means for receiving the solid material dumped from said belt, means arranged between the pulleys and beneath the belt for receiving the liquid material that passes through the belt, tamping devices between said pulleys and between the belt for tamping the belt to dislodge solid material therefrom, and means for driving said belt and said tamping devices, substantially as shown and described.
